VALVE FOR NURSING BOTTLES

Edward Geistlinger, Peekskill, N. Y.

Application November 10, 1933, Serial No. 697,411

5 Claims. (Cl. 251—139)

This invention relates generally to nursing bottles and particularly to a venting valve device for nursing bottles.

The invention resides more particularly in the particular construction of the valve device whereby certain objections to the valves in the prior art are overcome. These objections will be later pointed out.

It is well known that much of the difficulty of nursing children is caused by the high vacuum created due to the improper supply of air to replace the withdrawn liquid. Valves have been provided to overcome this difficulty and in so doing other problems are introduced which have not been solved up to the present time.

These valve devices are usually placed near the bottom of the bottle. When the bottle is upright the liquid escapes thru these devices. If the device is provided with spring means to overcome this leak then the entral pressure difference is increased. That is, the pressure inside the bottle must be reduced by an amount equal to the sealing spring pressure before any air is admitted into the bottle. The nipples of nursing bottles being of soft rubber, may be caused to flatten, during the withdrawal of liquid and in overcom-

ing this pressure difference.

The main object of the present invention is to improve the valve devices of bottles whereby the difficulty of withdrawing liquid is eliminated and the tendency of the nipple to flatten is prevented. This invention further precludes the leaking of the device in the event of the bottle being used with the valve below the liquid level; or, when the bottle is in an upright position.

Another object of the invention is to provide a valve device of the character described having the valve member anchored to the cap of the device to prevent displacement of the valve member, when the device is disassembled, and at the same time, permitting the valve member freedom of movement in response to slightest pressure difference when in use.

Another object of the invention is to provide a device of the character described that functions as a vent only, when the device in use is above the liquid level; and when below the level of the liquid, functions as a vent during the entire suction impulse, to permit air to enter, and as a valve, to prevent the escape of liquid between suction impulses.

Other objects and advantages will become apparent as the invention is further disclosed in the following description read in connection with the accompanying drawing.

While the drawing illustrates one embodiment of the invention it is to be understood that various changes may be made without departing from the spirit and scope of the claims hereunto appended.

Referring to the drawing:

Figure 1 is a side view of a nursing bottle with the invention applied thereto.

Figure 2 is a sectional view of the device, in closed or sealed position.

Figure 3 is a similar view but with the parts in operative position during a suction impulse.

Figure 4 is a view similar to Fig. 3 showing a modified form thereof.

Figure 5 is a further modification.

The reference character 10 designates a nursing bottle adapted to receive a nipple 11. The form of the bottle or nipple is not limited to that shown. Adapted to be secured to the bottle 10, preferably on the side and near the bottom thereof, is a vent-valve device 12. This device comprises a neck member 13 having a passage 14 therein; a thread 15, and a flange 16. A hole 17 is provided in the bottle to receive this neck member 13, which is inserted from the inside of the bottle. A gasket 18 is provided on the neck member to lie between the flange 16 and the inner wall of the bottle. Another gasket 19 is adapted to fit around the neck member 13 and is arranged to lie adjacent the outer wall of the bottle.

A sleeve 20, having internal threads 21 adapted to engage the threads 15, is provided to effect a seal around the hole 17 of the bottle. This sleeve is provided with a polygonal flange 21a for the application of a wrench or the like to compress the gaskets 18 and 19 between the flanges 16 and 21a. The sleeve 20 is further provided with an external thread 22, to receive a cap 23.

The sleeve extends outwardly beyond the neck 40 and provides a flat face 24, the purpose of which will be more fully described hereinafter. It is to be understood however, that the neck member 13 may extend beyond the sleeve member 20, to provide this flat face.

The cap 23 is provided with an internal thread 24a, adapted to fit, and snugly engage the thread 22 of the sleeve so as to be substantially leak proof. The cap is of cylindrical section having an end wall or closure 23a. In the end wall, an opening 25 is provided to receive a valve member 26. This valve member comprises a shank 27 adapted to fit loosely in the opening 25, and is further provided with an enlarged disc shaped head 28 on the inner-side of the end wall; and 55

an enlarged rivet head 28 is provided on the outer side of the end wall 23a. The length of the shank 27 is greater than the thickness of the end wall and the enlargements on either side of the end 5 wall permits freedom of movement of the valve member in the cap between the limits of these enlargements.

The inner face 30 of the end wall is finished smooth, as well as the faces of the disc 28, to 10 effect a double seal between the sleeve 20 and the cap 23 when the cap is screwed tightly to the sleeve, as shown in Fig. 2. The parts in this figure are in closed position and are ordinarily kept in this position, except during the nursing 15 period.

The parts as seen in Fig. 3 are in open position, which is the proper position during the nursing period. Preferably, the cap is loosened about one-quarter of a turn to the left, which 20 frees the valve member so that it may move freely during the nursing period. The bottle, when in use, may be in any of a number of positions, the valve may be below the liquid level or above. When the bottle is in use with the device 25 above the liquid level, it acts as a vent, that is, the valve member remains substantially in the position shown in Fig. 3. The air enters between the shank 27 and the wall of the opening 25. Suitable slots 31 may be provided and extend 30 beyond the confines of the rivet to facilitate the entry of air. These slots may be made in the rivet end of the valve member if desired.

When the bottle is in use with the device below 35 the liquid level, the valve member acts as a vent during the suction impulses and as a check valve between suction impulses, to prevent the escape of liquid thru the opening 25. It will be seen that with the construction of the device shown 40 the valve member is responsive to the slight pressure differences between the inside and outside of the bottle, which construction prevents a partial vacuum being created within the bottle during the sucking impulse of the infant. The valve will open immediately upon withdrawal of 45 liquid and will close against the face 30 due to the liquid head, immediately thereafter, due to its freedom of movement in the device.

When the bottle is not in use for a long period, 50 as would occur when the bottles are prepared and placed in a refrigerator, for later consumption, leakage is prevented by the positive seal provided by the contact between the disc 28 and the annular face of small contacting area presented to this disc.

55 In the modification shown in Fig. 4, a compressible gasket 32 may be provided between the flange 21a and the annular face provided by the cap on the inner face of the cylindrical portion thereof. This gasket will prevent any leakage 60 due to close fitting of the threads of the cap when the parts are in operative position.

Fig. 5 is a further modification showing the 65 simplicity with which means may be provided to prevent the infant from tampering with the adjusted position of the cap. A washer shaped member 33 having a projection 34 is clamped between the flange 21a and the gasket 19. This projection is bent and adapted to yieldably engage the knurled periphery of the cap.

70 It will be seen that the present valve is simple in construction and easy to manufacture. The valve is effective to prevent leakage during handling or storing of the bottled contents and also while the infant is nursing. The bottle may be 75 placed in water to warm the contents, without

danger of leakage or contamination of the food 5 therein. The parts may be readily sterilized without disassembly thereof and are rigid in construction and fully capable of withstanding the rough usage to which they may be subjected.

As various changes may be made in the form, 10 construction and arrangement of the parts herein without departing from the spirit and scope of the invention and without sacrificing any of its advantages, it is to be understood that all matter 15 herein is to be interpreted as illustrative and not in a limiting sense.

Having thus described the invention, what is 20 claimed and desired to secure by Letters Patent, 25 is:—

1. In a device of the class described, the combination of a threaded apertured member adapted to extend through an aperture in the wall of a bottle, said member having an outwardly extending flange adapted to engage the bottle adjacent the aperture therein, a second apertured member having a thread to mate with the thread on said first member and to secure said first member rigidly in the aperture of the bottle and having an external thread to mate with a closure, 30 an apertured closure threaded to said second member, and a floating disc having a shank extending through the aperture in the closure to give a limited movement to the disc for opening and closing the aperture in said first apertured 35 member.

2. In a device of the class described, the combination of an exteriorly threaded member having a duct extending therethrough, said member being adapted to extend through an aperture in a bottle and having an integral flange thereon to engage the inside of the bottle about said aperture, an interiorly and exteriorly threaded collar attached to said threaded member adapted to be positioned about the aperture on the outside of the 40 bottle to hold said member in position, a cap having screw threads on the interior of the flange thereof adapted to be screwed on said collar, said cap having an aperture in the cover part thereof, and an imperforate disc held in position by said 45 cap and adapted to act as a valve member to open and close said duct.

3. In a vent valve of the class described, the combination of a flanged member having a screw 50 thread thereon adapted to extend through an aperture in a nursing bottle with said flange fitting about the aperture on the inside of the bottle, a threaded collar member threaded to the exterior of said tubular member for engaging the exterior of the bottle to hold the tubular member in place, a 55 cap having a screw thread on the interior thereof threaded to the exterior of one of said members and having an aperture in the cover thereof, and a freely floating disc having an integral member movably mounted and permanently secured in said 60 aperture, the cooperating screw threads on the cap and on the one of the said members providing for clamping said disc in closed position, said disc being adapted to act as a valve for closing the end 65 of one of said members.

4. In a vent valve of the class described, the combination of a flanged tubular member having screw means thereon adapted to extend through an aperture in a nursing bottle with said flange fitting about the aperture on the inside of the 70 bottle, a collar member on the exterior of the bottle having screw means thereon in engagement with the screw means on the tubular member to hold the tubular member in place, a cap having screw means on the interior thereof in engage- 75

ment with the screw means on the exterior of one of said members, and having an aperture in the cover thereof and a freely floating disc having an integral member movably mounted and permanently secured in said aperture, the cooperating screw means on the cap and on one of the said members providing for clamping said disc in closed position, said disc being adapted to act as a valve for closing the end of one of said members.

10 5. In a vent valve of the class described, the combination of an externally threaded flanged tubular member adapted to extend through an aperture in a nursing bottle with a flange on the interior of the bottle, an annular gasket fitting about said tubular member adjacent said aperture, an interiorly threaded collar member thread-

ed about said tubular member for engaging the exterior of the bottle to fix it in the aperture and to compress the said gasket about the aperture, an interiorly threaded closure cap adapted to be threaded on one of said members and having an aperture in the cover thereof, a freely floating disc having an integral member movably mounted and permanently secured in said aperture, the co-operating screw threads on the cap and on one of the said members providing for clamping 10 said disc in closed position, said disc being adapted to act as a valve for closing the end of one of said members, and means attached to one of said members adapted to engage the closure cap to resist rotation thereof. 15
